Attorney.

UNITED STATES PATENT OFFICE.

JOHNSON MILLS, OF PRESTWICH, COUNTY OF LANCASTER, ENGLAND.

WATER-TUBE STEAM-BOILER.

SPECIFICATION forming part of Letters Patent No. 423,790, dated March 18, 1890.

Application filed November 8, 1889. Serial No. 329,693. (No model.) Patented in England May 12, 1888, No. 7,077, and in France May 10, 1889, No. 198,049.

To all whom it may concern:

Be it known that I, JOHNSON MILLS, a subject of the Queen of Great Britain, and a resident of Prestwich, in the county of Lancaster, England, have invented certain new and useful improvements in Water-Tube Steam-Boilers, (for which I have obtained a patent in Great Britain, No. 7,077, dated May 12, A. D. 1888, and in France, No. 198,049, dated May 10, 1889,) of which the following is a full, clear, and exact specification.

The improvements which are the subject of this invention relate to the application to water-tube steam-boilers of a water-chambered fire box or boxes, which are or may be of the flue-tube construction or other suitable form, in combination with tubes and pipes for connection with and to said water-tube steam-boilers, these water-chambered fire-boxes in their connection to and combination with water-tube steam-boilers being placed in the position usually occupied by the furnaces of water-tube steam-boilers. This combination of fire box or boxes with the tubes or pipes attached thereto are connected to and in combination with the several tubes and drums of water-tube steam-boilers.

The objects of this invention are to utilize in the generation of steam the greatest possible amount of heat given off in radiation while the fuel is in combustion and to save the very heavy and frequent expense of renewing the brick-work which is requisite to furnaces of water-tube steam-boilers.

By the arrangement of flue-furnace, which in this invention is formed by the water chamber or tube which surrounds the fire, the radiant heat is more efficiently absorbed and utilized in the production of steam in lieu of being largely wasted, as hitherto, by absorption with brick walls, which in the present form of construction inclose the furnaces of water-tube steam-boilers, and the hot gases which are produced by the complete combustion of the fuel passed forward through the several sets or nests or parts of the water-tube steam-boiler and are thoroughly utilized.

In order more clearly to describe this my invention, I have annexed hereunto three sheets of drawings. In the several views

therein shown similar letters refer to similar parts.

Figure 1 is a transverse section, and Fig. 2 a longitudinal section, of a water-tube steam-boiler provided with my improvements. Figs. 3 and 4 and 5 and 6 are respectively transverse and longitudinal sections of the same with slight modifications. Figs. 7 and 8 are transverse and longitudinal sections, which will be hereinafter more particularly referred to. Figs. 9 and 10 are longitudinal sections showing modifications.

The sectional line of Fig. 1 is taken through the line A B on Fig. 2, and the sectional line of Fig. 2 is drawn through the line C D on Fig. 1.

In the drawings, A is the steam and water drum.

B' and B² are tubes which are parts of existing forms of water-tube steam-boilers, and through which the water circulates.

b and b³ are tubes which I employ to form connections between the water-chamber e and the drums, tubes, or slabs of water of water-tube steam-boilers.

c is the flue-furnace, which I construct, preferably, of a cylindrical form, and which may be either a flanged-seam furnace, as shown in Fig. 8, or Fox's patent corrugated flue, as represented in Figs. 1 to 6, or of any other suitable construction.

d is the water-casing, which I form of steel or iron of any strength that may be required. The space e thus left between the flue-furnace c and the outer casing or shell d, and which may vary more or less in capacity according to requirements, I use as a water-chamber. The heat which rises from the combustion of the fuel in the furnace c is utilized in the generation of steam from the water contained in the chamber e, which surrounds the furnace c, instead of being absorbed and wasted by the brick walls of which the furnaces in water-tube steam-boilers are composed. As the water in the chamber e is increased in temperature it becomes expanded and sets up a circulation through the several parts of the boiler.

I place a mud and water drum f in a transverse position at the rear end of the boiler,

and I connect said mud and water drum with the water-chamber *e* of the flue-tube fire-box by means of the tubes *b*³, and to rear end of steam and water drum *d* and the tubes *b*² by means of long nipples *b*', which are expanded in their respective positions. In forming the connection between the upper part of water-chamber *e* of flue-tube fire-box and the front portion of steam and water drum *d* any preferable means may be employed.

The connection between the water-chamber *e* of flue-tube fire-box and the mud and water drum *f* may be formed either by means of tubes *b*³, as shown in Fig. 2, hereinbefore described, or with flanged wrought-iron, steel, or other metal tubes or pipes *b*', as shown in Figs. 9 and 10, Sheet 3. The tubes *b*³ or pipes *b*' may also be connected with the steam and water drum at the rear end of the boiler by means of tubes or pipes direct in lieu of passing through the tubes *b*' and rear headers.

The hereinabove-described flue-tube fire-box may be supported by girders *J*, by brack-

ets, or by other suitable appliances, or may be supported either whole or in part by the tubes *b*, which connect said fire-box to steam and water drum.

Having now particularly described and ascertained the nature of my said invention and in what manner the same is to be performed, I declare that what I claim is—

In a sectional tube-boiler having inclined water-tubes connected to the headers, said headers being connected to the steam and water drum, a flue-furnace surrounded by a water-chamber which is connected with the steam and water drum and with the mud-drum, as set forth.

In testimony that I claim the foregoing I have hereunto set my hand this 4th day of September, 1889.

JOHNSON MILLS.
